(57) **ABSTRACT**

A timepiece includes a case and a movement disposed in the case, the movement including a main plate, a train wheel disposed at the main plate and including a plurality of toothed gears, a train wheel bridge holding the train wheel, and a first magnetic shield component disposed between the main plate and the train wheel bridge in a side view as viewed from a direction parallel to a surface of the main plate. The first magnetic shield component, in plan view, has an annular shape and is disposed inwardly of an outer periphery of the main plate and, in the side view, is disposed within a range in which the wheel train is disposed. At least a portion of the train wheel is disposed on an inner side of the annular shape in the plan view.

TIME PIECE HAVING A MAGNETIC SHIELD

The present application is based on, and claims priority from JP Application Serial Number 2022-121345, filed Jul. 29, 2022, the disclosure of which is hereby incorporated by reference herein in its entirety.

BACKGROUND

1. Technical Field

The present disclosure relates to a timepiece.

2. Related Art

JP-A-2001-108764 discloses a configuration of an electronically controlled mechanical timepiece including magnetic shield plates capable of shielding against a magnetic field from the outside. Specifically, the magnetic shield plates are disposed on a case back side of a movement and on an outer peripheral side of the movement.

However, in the technique described in JP-A-2001-108764, because the magnetic shield plates are disposed on the case back side and the outer peripheral side of the movement, the timepiece is thick and an outer diameter dimension of the timepiece is large. That is, there is a demand for a timepiece that can be reduced in thickness and reduced in diameter while maintaining a magnetic shield performance.

SUMMARY

A timepiece includes a case and a movement disposed in the case, the movement including a main plate, a train wheel disposed at the main plate and including a plurality of toothed gears, a train wheel bridge holding the train wheel, and a first magnetic shield component disposed between the main plate and the train wheel bridge in a side view as viewed from a direction parallel to a surface of the main plate. The first magnetic shield component, in plan view as viewed from a direction perpendicular to the surface of the main plate, has an annular shape and is disposed inwardly of an outer periphery of the main plate and, in the side view, is disposed within a range in which the wheel train is disposed. At least a portion of the train wheel is disposed on an inner side of the first magnetic shield component in the plan view.

BRIEF DESCRIPTION OF THE DRAWINGS

FIG. 1 is a plan view illustrating a configuration of a dial side of a timepiece.

FIG. 2 is a plan view illustrating a configuration of a case back side of the timepiece.

FIG. 3 is a plan view illustrating a dial side of a movement.

FIG. 4 is a plan view illustrating a state in which a date indicator of the movement is removed.

FIG. 5 is a cross-sectional view taken along line D-D of the movement illustrated in FIGS. 2 and 7.

FIG. 6 is a plan view illustrating a case back side of the movement.

FIG. 7 is a plan view illustrating a state in which a train wheel bridge of the movement is removed.

FIG. 8A is a plan view illustrating a configuration of a first magnetic shield component.

FIG. 8B is a cross-sectional view of the first magnetic shield component taken along line A-A illustrated in FIG. 8A.

FIG. 8C is a cross-sectional view of the first magnetic shield component taken along line B-B illustrated in FIG. 8A.

FIG. 9A is a plan view illustrating a configuration of a second magnetic shield component.

FIG. 9B is a cross-sectional view of the second magnetic shield component taken along line C-C illustrated in FIG. 9A.

FIG. 10 is a perspective view illustrating in an enlarged manner a portion E of the movement illustrated in FIG. 7.

FIG. 11 is a perspective view illustrating in an enlarged manner a portion F of the movement illustrated in FIG. 7.

FIG. 12 is a graph showing a relationship between an intensity of an external magnetic field and a magnetic flux density flowing through a stator.

FIG. 13A is a cross-sectional view illustrating a fixing method according to a modification.

FIG. 13B is a cross-sectional view illustrating a fixing method according to a modification.

FIG. 13C is a cross-sectional view illustrating a fixing method according to a modification.

DESCRIPTION OF EXEMPLARY EMBODIMENTS

The following description is given with reference to the drawings including an X axis, a Y axis, and a Z axis that are three axes orthogonal to each other. A direction along the X axis is referred to as “X direction”, a direction along the Y axis is referred to as “Y direction”, and a direction along the Z axis is referred to as “Z direction”. A direction indicated by an arrow is a + direction, and a direction opposite to the + direction is a - direction. Note that, a +Z direction may be also referred to as “up” or an “upper side”, and a -Z direction may be also referred to as “down” or a “lower side”. Furthermore, the view in the +Z direction or the -Z direction is referred to as plan view or plane view. Furthermore, the description is given assuming that a surface on the + side in the Z direction is an upper surface, and a surface on the opposite side, that is, on the - side in the Z direction is a lower side.

First, a configuration of a timepiece 1 will be described with reference to FIGS. 1 and 2.

As illustrated in FIG. 1, the timepiece 1 is a wristwatch worn on a wrist of a user and includes a case 2 having a cylindrical shape. A dial 3 is disposed on an inner circumferential side of the case 2. Among two openings of the case 2, an opening on a front surface side is covered by a cover glass 8, and an opening on a back surface side is covered by a case back 9. Note that the case 2 and the case back 9 need not be separate bodies, and may be integrally formed.

As illustrated in FIG. 2, the case back 9 is constituted by a frame 9A having a ring shape and a case back glass 9B attached to the frame 9A. The timepiece 1 of this exemplary embodiment is a skeleton-type timepiece in which an oscillating weight 15 and a power reserve hand are visible from the case back 9 side of the timepiece 1.

The timepiece 1 includes a movement 10 (refer to FIG. 2) accommodated in the case 2, an hour hand 4A, a minute hand 4B, and a seconds hand 4C that display time information, and a power reserve hand that indicates the duration of a mainspring. The dial 3 is provided with a small calendar window 3A, and a date indicator 6 is visible through the small calendar window 3A. Further, the dial 3 is provided

with hour marks 3B for indicating the hour. A power reserve scale 5 having a fan shape is provided on the case back side of a train wheel bridge 25 described below. The power reserve hand points to this power reserve scale 5, making it possible to display the amount of winding left on the mainspring. Although not illustrated, the power reserve hand is attached so as to rotate about a center of the fan of the power reserve scale 5.

A crown 7 attached to a winding stem 12 (refer to FIG. 3) is provided on a side surface of the case 2. The crown 7 can be pulled out and moved from a zero position of being pushed in toward a center of the timepiece 1 to a first-step position and a second-step position. When the crown 7 is rotated in the zero position, the mainspring as a mechanical energy source provided in the movement 10 is wound. The power reserve hand moves in conjunction with the winding of the mainspring.

When the crown 7 is pulled to the first-step position and rotated, the date indicator 6 can be moved to set the date. When the crown 7 is pulled to the second-step position, the seconds hand 4C stops, and when the crown 7 is rotated in the second-step position, the hour hand 4A and the minute hand 4B can be moved to set the time.

As illustrated in FIG. 2, an opening 15B is formed in a weight body 15A of the oscillating weight 15, and is configured so that the power reserve hand indicating the amount of winding left on the mainspring is less likely to be invisible due to the position of the oscillating weight 15.

Next, a configuration of the movement 10 as viewed from the dial 3 side will be described with reference to FIGS. 3 to Here, the movement 10 refers to a structure assembled as a single unit, excluding exterior components such as the case 2, the dial 3, and the hands 4A to 4C from the timepiece 1, and including driving components for driving the hands 4A to 4C, such as a train wheel. Note that FIG. 4 illustrates a state in which the date indicator 6 is removed from the movement 10 illustrated in FIG. 3. The movement 10 illustrated in FIG. 5 is disposed with the side to which the dial 3 is attached (hereinafter referred to as the dial 3 side) facing downward.

As illustrated in FIGS. 3 and 4, in the movement 10, an hour wheel 21 is disposed at a main plate 11. The hour hand 4A is fixed to the hour wheel 21. A date indicator driving intermediate wheel is attached to the hour wheel 21, and a date indicator driving finger for rotating the date indicator 6 is attached to a date indicator driving wheel 22 rotated by the date indicator driving intermediate wheel.

As illustrated in FIG. 4, when the date indicator 6 is removed from the movement 10, a dial-side magnetic shield component 30 having an annular shape is disposed overlapping the date indicator 6. The dial-side magnetic shield component 30 is used for shielding against a magnetic field from the outside of the timepiece 1. Note that a coil block 24 is disposed under or on an inner side of the dial-side magnetic shield component 30 formed in an annular shape. This makes it possible to suppress the influence of a magnetic field from the dial 3 side on the coil block 24.

The dial-side magnetic shield component 30 is made of, for example, pure iron or permalloy.

Next, a configuration of the movement 10 as viewed from the case back 9 side will be described with reference to FIGS. 5 to 11. Note that FIG. 7 illustrates a state in which the train wheel bridge 25 is removed from the movement 10 illustrated in FIG. 6. As described above, the movement 10 illustrated in FIG. 5 is disposed so that the dial 3 side faces downward, that is, the case back 9 side faces upward.

As illustrated in FIGS. 6 and 7, the movement 10 as viewed from the case back 9 side includes a movement barrel complete 26 in which the mainspring is accommodated. The hour hand 4A, the minute hand 4B, and the seconds hand 4C are attached to the hour wheel 21, a cannon pinion, and a fourth wheel and pinion 54 of the movement 10, respectively, and are driven by the mainspring of the movement 10.

The movement 10 includes the main plate 11, a second bridge 27 (refer to FIG. 5), and the train wheel bridge 25 that holds the train wheel. The main plate 11, the second bridge 27, and the train wheel bridge 25 are flat plate-shaped components including surfaces. As illustrated in FIG. 5, between the main plate 11, the second bridge 27, and the train wheel bridge 25 are disposed a barrel accommodating the mainspring, a power reserve display mechanism, portions of a manual winding mechanism and an automatic winding mechanism for winding the mainspring, a display train wheel 50 for transmitting a torque of the mainspring, a generator 28 (refer to FIG. 5) driven by the torque transmitted via the display train wheel 50, and a printed wired board on which an integrated circuit (IC; not illustrated) driven by electric power from the generator 28 and configured to control a rotation period of the display train wheel 50.

As illustrated in FIG. 7, the generator 28 includes a rotor 40 and the coil block 24. The rotor 40 includes a rotor magnet 41, a rotor pinion 42, and a rotor inertia disk 43. As will be described below, the torque from the mainspring is transmitted to the rotor 40 via the display train wheel 50. The coil block 24 is constituted by a coil 24a and a stator 24b.

When the rotor 40 rotates by the torque of the mainspring, the generator 28 can generate induced power by the coil block 24, output electrical energy, and supply the electrical energy to the IC or the like. Further, a brake can be applied to the rotor 40 by short-circuiting the coil 24a, and the rotation period of the rotor 40, that is, the rotation period of the display train wheel 50, can be adjusted to a constant speed by controlling the braking force by the control by the IC.

As described above, the timepiece 1 according to the exemplary embodiment is configured as an electronically controlled mechanical timepiece that uses the rotation of the rotor 40 of the generator 28 that generates induced power, outputs electrical energy, and is utilized as a speed governor mechanism.

The barrel accommodates the mainspring and includes the movement barrel complete 26 and a barrel stem. A ratchet wheel 29 that rotates integrally with the barrel stem is attached to the barrel stem.

The automatic winding mechanism includes the oscillating weight 15 illustrated in FIG. 5, a bearing (not illustrated) that includes a gear that rotatably supports the oscillating weight 15 and rotates integrally with the oscillating weight 55 15, an eccentric wheel 57 illustrated in FIG. 7 that meshes with the gear of this bearing, a pawl lever, and the transmission wheel 58. When the oscillating weight 51 rotates, the ratchet wheel 29 coaxially attached to the movement barrel complete 26 rotates via the eccentric wheel 57, the 60 pawl lever, and the transmission wheel 58, thereby winding the mainspring accommodated in the movement barrel complete 26. Note that in this exemplary embodiment, description of the manual winding mechanism is omitted.

Next, the display train wheel 50 for driving the hour hand 4A, the minute hand 4B, and the seconds hand 4C by the mechanical energy from the mainspring will be described. As illustrated in FIG. 7, the display train wheel 50 includes

a center wheel and pinion, a third wheel and pinion 53, the fourth wheel and pinion 54, a fifth wheel and pinion 55, and a sixth wheel and pinion 56, and is disposed at the main plate 11. The rotation of the movement barrel complete 26 is transmitted to the center wheel and pinion and, after the third wheel and pinion 53, the fourth wheel and pinion 54, the fifth wheel and pinion 55, and the sixth wheel and pinion 56 are increased in speed sequentially, is transmitted to the rotor 40. The minute hand 4B is fixed to the center wheel and pinion via a cannon pinion. The seconds hand 4C is fixed to the fourth wheel and pinion 54. Further, the hour wheel 21 is coupled to the cannon pinion via the minute wheel. The hour hand 4A is fixed to this hour wheel 21.

Note that the barrel, the eccentric wheel 57, the pawl lever, and the transmission wheel 58 of the automatic winding mechanism, and the display train wheel 50 may be collectively referred to as the train wheel.

As illustrated in FIG. 7, a first magnetic shield component 31 is disposed on an inner side of an outer periphery of the main plate 11. That is, the first magnetic shield component 31 is disposed overlapping a portion of the stator 24b of the coil block 24 in plan view.

Further, the first magnetic shield component 31 is formed in an annular shape in plan view as viewed from the Z-axis direction perpendicular to a surface of the main plate 11, in other words, in plan view as viewed from the -Z direction. At least a portion of the train wheel is disposed on an inner side of the first magnetic shield component 31 in plan view. Specifically, at least the fourth wheel and pinion 54, the eccentric wheel 57, and the transmission wheel 58 are disposed on the inner side of the first magnetic shield component 31. In other words, the first magnetic shield component 31 having an annular shape is disposed so as to stay clear of a portion of the train wheel at a central portion of the movement 10.

Further, as illustrated in FIG. 5, the first magnetic shield component 31 is disposed between the main plate 11 and the train wheel bridge 25 in a side view as viewed from a direction parallel to a surface of the case back 9. Specifically, the first magnetic shield component 31 has the same height as a portion of the train wheel and is disposed within a range in which the train wheel is disposed in the Z direction perpendicular to a surface of the main plate 11.

Note that "same height" in this exemplary embodiment is not limited to a state in which the heights of some components such as the center wheel and pinion 52, the third wheel and pinion 53, the fourth wheel and pinion 54, the transmission wheel 58, the pawl lever, and the eccentric wheel 57 constituting the train wheel are flush with the height of the first magnetic shield component 31. For example, "same height" also includes, in a side view, a state in which the first magnetic shield component 31 overlaps some of the components, and a state in which the first magnetic shield component 31 is disposed at a position closer to the main plate than the component disposed closest to the case back among the components constituting the wheel train. In this exemplary embodiment, the first magnetic shield component 31 is disposed closer to the main plate than the eccentric wheel 57. That is, the first magnetic shield component 31 is disposed at a height within a range in the Z direction of the components constituting the train wheel in a side view, making it possible to reduce a thickness of the timepiece 1 compared to a case in which the magnetic shield component is disposed closer to the case back 9 than the movement 10 as in the related art.

As illustrated in FIG. 7, in plan view, a second magnetic shield component 32 is disposed on an outer side of the first

magnetic shield component 31 and on the inner side of the outer periphery of the main plate 11. Specifically, the second magnetic shield component 32 is disposed covering a portion of a side surface of the generator 28 (refer to FIG. 10). Furthermore, the second magnetic shield component 32 is in contact with a portion of the first magnetic shield component 31 (refer to FIG. 10).

Note that the first magnetic shield component 31 and the second magnetic shield component 32 are made of, for example, pure iron or permalloy, similar to the dial-side magnetic shield component 30.

As illustrated in FIGS. 8A, 8B, and 8C, the first magnetic shield component 31 having an annular shape includes a first main body portion 31a, a second main body portion 31b, a first contact portion 31c, and a second contact portion 31d. The second main body portion 31b is provided at a position higher than that of the first main body portion 31a with a step portion 31a1 interposed therebetween. The first contact portion 31c and the second contact portion 31d are provided at positions lower than that of the first main body portion 31a with a curved portion 31a2 interposed therebetween.

As illustrated in the FIGS. 9A and 9B, the second magnetic shield component 32 is formed so as to curve and thus surround one half of the first magnetic shield component 31 on the outer peripheral side. The second magnetic shield component 32 includes a first main body portion 32a, a second main body portion 32b, a first contact portion 32c, a second contact portion 32d, and a fixing portion 32e.

Specifically, the first main body portion 32a and the second main body portion 32b are disposed at the same height. The first contact portion 32c is provided at a position lower than that of the first body portion 32a with a step portion 32a1 interposed therebetween. The second contact portion 32d is provided at a position lower than that of the second main body portion 32b with a step portion 32b1 interposed therebetween. The fixing portion 32e is provided at a position lower than those of the first main body portion 32a and the second main body portion 32b with the step portions 32a2, 32b2 interposed therebetween.

That is, the first magnetic shield component 31 includes a step, the step being the step portion 31a1 in this exemplary embodiment, in an axial direction of the case 2, that is, the Z direction. The ratchet wheel 29, which is a portion of the train wheel, is disposed in the step formed by the step portion 31a1. In this way, a portion of the train wheel is disposed in the step of the first magnetic shield component 31, in other words, the first magnetic shield component 31 is contained within the range of the height of the train wheel, making it possible to dispose the first magnetic shield component 31 in the movement 10 while making the timepiece 1 thinner. Further, by providing the step, it is possible to form the first magnetic shield component 31 into a continuous annular shape without providing a notch for staying clear of the ratchet wheel 29 in the first magnetic shield component 31. Accordingly, as will be described below, it is possible to suppress the influence of a magnetic field from the outside on the stator 24b.

As illustrated in FIG. 7, the first magnetic shield component 31 and the second magnetic shield component 32 are in contact with each other at the first contact portion 31c and the first contact portion 32c in a portion E. The first magnetic shield component 31 and the second magnetic shield component 32 are fixed to, for example, the main plate 11 by a first lock screw 13a (refer to FIG. 10). On the other hand, the first magnetic shield component 31 and the second magnetic shield component 32 are in contact with each other at the second contact portion 31d and the second contact portion

32d at a portion F. Then, the first magnetic shield component **31** and the second magnetic shield component **32** are fixed to, for example, the main plate **11** by a second lock screw **13b** (refer to FIG. 11).

Further, the fixing portion **32e** of the second magnetic shield component **32** is fixed to the main plate **11** without the first magnetic shield component **31** being interposed theretwix. Note that the first magnetic shield component **31** and the second magnetic shield component **32** are not limited to being in contact with each other at two locations, and may be in contact with each other at three or more locations. Further, the contact is not limited to the contact at the first contact portions **31c**, **32c** and the second contact portions **31d**, **32d**, and may be at other portions.

With the first magnetic shield component **31** and the second magnetic shield component **32** thus disposed and being in contact with each other, it is possible to form a magnetic path without an air layer interposed between the first magnetic shield component **31** and the second magnetic shield component **32**, and enhance a magnetic shield performance. Further, with the first magnetic shield component **31** and the second magnetic shield component **32** incorporated in the movement **10**, the timepiece **1** can be made more compact than when the magnetic shield components are disposed between the movement **10** and the case **2**.

Further, as illustrated in FIG. 5, in the oscillating weight **15**, to facilitate smooth rotation, a thickness **L1** of an outer peripheral portion **15C** that is a weight is thicker than a thickness **L2** of the weight body **15A**. However, by lowering the outer peripheral portion **15C** in the Z direction in alignment with the step of the first magnetic shield portion **31**, it is possible to reduce the thickness of the timepiece **1** compared to when the outer peripheral portion **15C** is thick in the +Z direction and thus the thickness of the timepiece **1** is increased as in the related art.

Next, an extent of influence that magnetic flux density has on, for example, the stator **24b** constituting the coil block **24**, with the first magnetic shield component **31** being disposed will be described with reference to FIG. 12.

FIG. 12 is a graph showing results of magnetic field analysis obtained by analyzing a relationship between an intensity (G) of a magnetic field received from the outside and a magnetic flux density (T) generated in the stator **24b** for the first magnetic shield components **31** having different shapes. The horizontal axis represents the intensity (G) of the magnetic field received from the outside, and the magnetic field increases in magnitude rightward. The vertical axis represents the magnetic flux density (T) generated at the stator **24b**, and the magnetic flux density increases upward.

The magnetic shield components used in the magnetic field analysis had five shapes: a ring shape (that is, annular shape), a C-ring shape in which a portion of the ring is missing, a rectangle having a narrow width, a rectangle **1** having a wide width, and a rectangle **2** having a wide width. Note that as an analysis condition, because the magnetic shield performance depends on the volume of the magnetic shield component, the magnetic shield components were formed into a plate shape having a uniform thickness across the entire shape. Then, all shapes excluding the rectangle **2** having a wide width were given the same volume, and only the rectangle **2** having a wide width was given a volume smaller than that of the other shapes due to the length thereof being shorter than that of the rectangle **1** having a wide width. The magnetic shield components were then each arranged overlapping the stator of the coil block.

As shown in FIG. 12, the most effective shape was the ring shape that had a low magnetic flux density affecting the

stator **24b** even when the intensity of the external magnetic field was high. The shape of the first magnetic shield component **31** was annular as in this exemplary embodiment, making it possible to minimize the influence of the magnetic field from the outside.

As described above, the timepiece **1** according to the exemplary embodiment includes the case **2** and the movement **10** disposed in the case **2**, the movement **10** including the main plate **11**, the train wheel disposed at the main plate **11** and including the plurality of toothed gears, the train wheel bridge **25** holding the train wheel, and the first magnetic shield component **31** disposed between the main plate **11** and the train wheel bridge **25** in a side view as viewed from the direction parallel to the surface of the main plate **11**. The first magnetic shield component **31**, in plan view as viewed from the direction perpendicular to the surface of the main plate **11**, has an annular shape and is disposed inwardly of the outer periphery of the main plate **11** and, in the side view, is disposed within a range in which the wheel train is disposed. At least a portion of the train wheel is disposed on an inner side of the first magnetic shield component **31** in the plan view.

According to this configuration, the first magnetic shield component **31** is disposed inwardly of the outer periphery of the main plate **11** in plan view and is disposed within the range in which the train wheel is disposed in a side view, making it possible to reduce the outer diameter dimension (reduce the diameter) of the timepiece **1** and reduce the thickness of the timepiece **1** while maintaining the magnetic shield performance.

Further, in the timepiece **1** according to the exemplary embodiment, the movement **10** may include the mainspring and the generator **28** driven by the mainspring to generate electrical energy, and the first magnetic shield component **31** may cover a portion on the case back **9** side of the generator **28**. According to this configuration, in the timepiece **1** including the mechanical energy source and the generator **28**, the first magnetic shield component **31** covers a portion of the generator **28**, making it possible to suppress the influence of a magnetic field from the outside on the generator **28** and maintain the magnetic shield performance. In addition, the timepiece **1** can be reduced in size.

Further, in the timepiece **1** according to the exemplary embodiment, the movement **10** may include the second magnetic shield component **32** that covers a portion of a side surface of the generator **28**, and the second magnetic shield component **32** covers the portion of the side surface of the generator **28**, is disposed inwardly of the outer periphery of the main plate **11** in the plan view, and is in contact with a portion of the first magnetic shield component **31**. According to this configuration, the second magnetic shield component **32** disposed inwardly of the outer periphery of the main plate **11** is in contact with a portion of the first magnetic shield component **31**, making it possible to form a magnetic path without an air layer between the second magnetic shield component **32** and the first magnetic shield component **31**. This makes it possible to increase the magnetic shield performance while reducing the size of the timepiece **1**.

Further, in the timepiece **1** according to the exemplary embodiment, the first magnetic shield component **31** may include the step in the direction perpendicular to the surface of the main plate **11**, and a portion of the train wheel may be disposed in the step. According to this configuration, a portion of the train wheel is disposed in the step of the first magnetic shield component **31**, in other words, the first magnetic shield component **31** is contained within the range of the height of the train wheel, making it possible to dispose

the first magnetic shield component 31 in the movement 10 while making the timepiece 1 thinner.

Modifications of the exemplary embodiment described above will be described below.

In the exemplary embodiment described above, as the structure in which the magnetic path is formed without an air layer interposed between the first magnetic shield component 31 and the second magnetic shield component 32, a structure in which the first magnetic shield component 31 and the second magnetic shield component 32 are in contact with each other and fixed by the first lock screw 13a and the second lock screw 13b has been described, but the structure is not limited thereto. For example, the structure may be configured as illustrated in FIGS. 13A to 13C.

FIG. 13A illustrates a structure in which the first magnetic shield component 31 is in contact with the second magnetic shield component 32 by being pressed thereagainst by a spring force. FIG. 13B illustrates a structure in which the first magnetic shield component 31 and the second magnetic shield component 32 are in contact with and fixed to each other, with a protruding portion formed at the first magnetic shield component 31 fitted into a hole formed in the second magnetic shield component 32. Note that the first magnetic shield component 31 and the second magnetic shield component 32 may be arranged in an opposite manner. FIG. 13C illustrates a structure in which the first magnetic shield component 31 and the second magnetic shield component 32 are in contact with and fixed to each other using a clamping component 14. According to these methods, it is possible to form a magnetic conduction path without an air layer interposed between the first magnetic shield component 31 and the second magnetic shield component 32, and enhance the magnetic shield performance.

In the exemplary embodiment described above, the timepiece 1 is described as an electronically controlled mechanical timepiece including the mainspring, the generator 28 driven by the mainspring to generate electrical energy, and the IC that controls the rotation speed of the display train wheel 50, but the embodiment is not limited thereto. For example, the present disclosure may be applied to a timepiece that does not include the generator 28 but includes a mechanical energy source including the mainspring, the oscillating weight 15, an automatic winding train wheel that winds the mainspring based on the rotation of the oscillating weight 15, and a speed governor such as a balance with a hairspring.

According to this configuration, in a mechanical timepiece, it is possible to achieve both maintenance of the magnetic shield performance and miniaturization of the timepiece.

What is claimed is:

1. A timepiece comprising:
a case; and
a movement disposed in the case, the movement including

a main plate,
a train wheel disposed at the main plate and including
a plurality of toothed gears,
a train wheel bridge holding the train wheel, and
a first magnetic shield component disposed between the
main plate and the train wheel bridge in a side view
as viewed from a direction parallel to a surface of the
main plate, wherein

the first magnetic shield component, in plan view as
viewed from a direction perpendicular to the surface of
the main plate, has an annular shape and is disposed
inwardly of an outer periphery of the main plate and, in
the side view, is disposed within a range in which the
wheel train is disposed and
at least a portion of the train wheel is disposed on an inner
side of the first magnetic shield component in the plan
view.

2. The timepiece according to claim 1, wherein
the movement includes
a mechanical energy source including a mainspring,
an oscillating weight, and
an automatic winding train wheel configured to wind
the mainspring based on a rotation of the oscillating
weight and

the train wheel is a self-winding train wheel.

3. The timepiece according to claim 1, wherein
the movement includes
a mechanical energy source and
a generator driven by the mechanical energy source to
generate electrical energy and

the first magnetic shield component covers a portion on a
case back side of the generator.

4. The timepiece according to claim 3, wherein
the movement includes a second magnetic shield compo-
nent and
the second magnetic shield component covers a portion of
a side surface of the generator, is disposed inwardly of
the outer periphery of the main plate in the plan view,
and is in contact with a portion of the first magnetic
shield component.

5. The timepiece according to claim 3, wherein
the first magnetic shield component includes a step in the
direction perpendicular to the surface of the main plate
and
a portion of the train wheel is disposed in the step.
